UNITED STATES PATENT OFFICE.

WILLIAM S. ISHAM, OF MAPLEHILL, KANSAS, ASSIGNOR OF TWO-THIRDS TO
JOSEPH N. DOLLY AND HARRY R. WILLIAMS, OF MAPLEHILL, KANSAS.

MAIL-DELIVERY BOX.

SPECIFICATION forming part of Letters Patent No. 734,266, dated July 21, 1903.

Application filed March 18, 1903. Serial No. 148,341. (No model.)

To all whom it may concern:

Be it known that I, WILLIAM S. ISHAM, a citizen of the United States of America, residing at Maplehill, in the county of Wabaunsee, and State of Kansas, have invented new and useful Improvements in Mail-Delivery Boxes, of which the following is a specification.

The invention has special reference to rural mail-delivery boxes, the object being to provide such a box which is simple and economic in construction, which may readily be opened and closed by the carrier, which is proof against the elements, especially rain, snow, and ice:

15 The invention consists of the novel combination, arrangement, and disposition of the parts, the preferred form of the embodiment whereof is herein described and claimed and is shown in the accompanying drawings, 20 forming part of this specification.

Figure 1 is a front elevation of the box with a vertical central longitudinal section of the right end thereof. Fig. 2 is a side elevation of the box. Fig. 3 is a cross-section through 25 the line *x y* of Figs. 1 and 5. Fig. 4 is a side elevation of the box open. Fig. 5 is a top view of a portion of the box and frame.

Like letters and figures of reference indicate like parts throughout the several views.

30 E may represent the post on which the box is mounted. D may be a board attached to the top of the post.

C is the frame or bracket for the box, attached to the side of the lower member.

35 B is a lower semicylinder mounted on the frame or bracket C and having the circular ends 34.

A is an upper semicylinder having circular ends 1 2 pivoted, 5, to the circular ends of the 40 lower semicylinder.

The upper semicylinder A incloses the ends and overlaps the sides of the lower semicylinder, fitting snugly thereto, so that the elements—the rain or the snow or the ice—can neither enter the box nor 45 clog the same. The sides of the upper and lower members may be beaded, 6 7 8 9, as shown, and the front edge 9 of the upper member may be bent slightly inward, Fig. 3, so as to tightly engage the adjoining side 8 of 50 the lower member. The frame or bracket C has a staple 10, and the upper or movable

member A has a hasp 11, whereby the upper member may be opened or closed and the box fastened or locked.

To operate the box, the carrier simply lifts 55 the hasp or handle 11, causing the upper member to oscillate about the lower member. If constructed in about the proportions shown in the drawings, the opening will be about one hundred and twenty degrees, which is ample 60 for ordinary purposes. The box is closed by simply pulling the hasp around again, so as to bring the upper member to its normal position, as shown in Figs. 1, 2, 3, 5.

If desired, a clip or shelf 13 may be provided inside the box for delivering outgoing mail to the carrier, and another clip 12 may be used for mounting a flag. It is understood, of course, that although the two main members are described herein as "semicylindrical," this term is used only approximately, for, as shown, the members actually overlap to some extent, and the members may vary slightly from semicylindrical according to the opening required, and there may be other 75 variations from the exact description shown herein and in the drawings without departing from the spirit of the invention.

What I claim as new, and desire to secure by Letters Patent, is—

1. The mail-delivery box consisting of the combination of the lower semicylindrical member having its opening facing upward; the supporting-bracket attached to the lower forward quarter of the lower member, and a 85 support for the bracket extending rearwardly underneath the lower member but not touching the same; the upper semicylindrical member whose side edges overlap the corresponding edges of the lower member, the front 90 edge of the upper member being bent inwardly to frictionally engage the edge of the lower member to form a locking device therefor; a suitable lifting device for the upper member; both lower and upper members 95 having concentric circular ends, pivoted together at the center, the ends of the upper member inclosing the ends of the lower member; whereby the upper member is adapted to form a lid for, and to oscillate about, the 100 lower member.

2. The mail-delivery box consisting of the

combination of the lower inner semicylindrical member having its opening facing upward; the supporting-bracket attached to the outer lower forward quarter of the lower member, and a support for the bracket extending rearwardly therefrom but spaced apart from the lower member; the upper outer semicylindrical member having its opening facing downward whose side edges overlap those of the lower member, the front edge of the upper member being bent inwardly to frictionally engage the adjoining edge of the lower member in their closed position; the supporting-bracket being provided with a staple and

the upper member being provided with a hasp 15 to engage the staple in the closed position; both lower and upper members having concentric circular ends, pivoted together at the center, whereby the upper outer member is adapted to oscillate about, and form a lid for, 20 the inner lower member.

In testimony whereof I have affixed my signature in the presence of two witnesses.

WILLIAM S. ISHAM.
